UNITED STATES PATENT OFFICE.

LERNER TEMPLIN, OF FLORENCE, COLORADO.

TOY REVOLVER.

SPECIFICATION forming part of Letters Patent No. 651,399, dated June 12, 1900.

Application filed February 2, 1900. Serial No. 3,725. (No model.)

To all whom it may concern:

Be it known that I, LERNER TEMPLIN, a citizen of the United States, residing at Florence, in the county of Fremont and State of Colorado, have invented certain new and useful Improvements in Toy Revolvers, of which the following is a specification.

My invention relates to toy revolvers, the object being to provide a device of this character of simple and inexpensive construction employing a revolving cylinder having peripheral pockets to contain explosive caps and means for imparting a partial revolution to the cylinder by the cocking of the revolver.

15 The construction of the improvement will be fully described hereinafter and defined in the appended claim, in connection with the accompanying drawings, which form a part of this specification, and in which—

20 Figure 1 is a side elevation of the revolver with one-half of its casing removed to show the mechanism. Fig. 2 is a plan view of the device. Fig. 3 is a side elevation of the revolvable cylinder. Fig. 4 is an edge view of the cylinder, and Fig. 5 is a plan view of the hammer and parts attached thereto detached from the shell.

25 The shell or casing of the revolver preferably consists of two hollow longitudinal sections 1 and 2, secured together by rivets 3.

4 designates the revolvable cylinder of the device, loosely mounted upon a transverse pin or shaft 5, fixed in bearings of the shell. A portion of the periphery of the cylinder is 30 milled or formed with transverse ribs, as shown at 6, to facilitate the turning of the cylinder by hand in loading it. Adjacent to the annular milled surface 6 the cylinder is formed with equidistant peripheral pockets 7, the walls 8 of which are beveled or undercut to engage the caps and retain them in position.

Upon the shaft 5, concentric with the cylinder 4 and preferably made integral therewith, is a ratchet-wheel 9, the teeth of which have their outer surfaces beveled and are adapted to be engaged by a dog 10, loosely pivoted to one side of an extension 11 of the trigger, said extension being provided with lugs 12 and 13, between which the dog 10 is

guided. A spring 14 is secured at one end to the side of the dog and its free end 15 is curved outward to bear against the adjacent side of the shell.

55 The hammer 16 and trigger 17, which are preferably formed of a single piece, are pivotally secured within the shell or casing by a pivot pin or bolt 18, and below said pivot 18 the rear side of the hammer is formed with a notch 19 to receive the forward end of the mainspring 20, the rear end of which is held in a notch 21, formed in the handle portion of the shell or casing.

22 designates a spring secured in front of the cylinder 4 in position to bear against the milled surface 6, the ends of said spring being held in place between suitable lugs 23 and 24, as shown in Fig. 1. This spring 22 serves as a brake to limit or impede the rotary movement of the cylinder.

70 The upper side of the section 1 of the shell is slotted at the point 25 for the passage of the hammer, and the shell 2 is slotted at the point 26 to present the milled surface of the cylinder in position to be turned by the thumb or finger.

75 The utility and operation of the revolver will be readily understood. The pockets of the cylinder are charged with paper caps by inserting the latter from the right side of the cylinder, and the form of said pockets prevents the caps from dropping out as the cylinder revolves. The drawing back of the hammer causes the dog 10 to move the cylinder a partial revolution, thus bringing one of the pockets, with its contained cap, into the path of the hammer.

80 The construction described provides a positive movement of both the hammer and cylinder, and the latter is firmly held at the points to which it is adjusted by the dog by means of the friction-spring 22.

85 An important characteristic of the invention is that the caps are so separated from one another that there is no danger of the explosion of one cap igniting those contained in the adjacent pockets, thus rendering the revolver entirely safe.

90 A further advantage of the invention is that no specially-designed ammunition is required,

the ordinary paper caps now commonly used being well adapted for use with the revolver.

I claim—

In a toy revolver, the combination with a slotted casing, of a revoluble cylinder arranged therein; having peripheral pockets, and an annular milled surface; a ratchet-wheel concentric with said cylinder; a friction-spring bearing against said cylinder; a

spring-pressed hammer and trigger, and a spring-pressed pivoted dog adapted to engage the teeth of the ratchet-wheel.

In testimony whereof I affix my signature in presence of two witnesses.

LERNER TEMPLIN.
